Primary Examiner — Janice Patyk(74) *Attorney, Agent, or Firm* — Lowe Graham Jones PLLC(57) **CLAIM**

I claim the ornamental design for a combined lid and spoon rest, as shown and described.

DESCRIPTION

FIG. 1 is a top perspective view of a combined lid and spoon rest, showing my new design.

FIG. 2 is a front elevational view of the combined lid and spoon rest.

FIG. 3 is a rear elevational view of the combined lid and spoon rest.

FIG. 4 is a left side elevational view of the combined lid and spoon rest.

FIG. 5 is a right side elevational view of the combined lid and spoon rest.

FIG. 6 is a top plan view of the combined lid and spoon rest; and,

FIG. 7 is a bottom plan view of the combined lid and spoon rest.

The broken lines in the figures illustrate the portions of the design that form no part of the claimed design.
